D. W. DETWILER

COMBINED GRAIN CLEANER AND ELEVATOR

Filed July 23, 1925

Patented Aug. 7, 1928.

1,679,516

UNITED STATES PATENT OFFICE.

DANIEL W. DETWILER, OF ROSEBUD, ALBERTA, CANADA, ASSIGNOR TO WESTERN STEEL PRODUCTS LIMITED, OF WINNIPEG, CANADA, A CORPORATION.

COMBINED GRAIN CLEANER AND ELEVATOR.

Application filed July 23, 1925. Serial No. 45,508.

My invention is concerned with combined grain cleaners and elevators, and is designed more especially to produce an attachment for separators whereby as the thrashed small 5 grain is delivered from the cross conveyor at the bottom of the separator it will be elevated the proper height to be discharged into wagons, and as it is elevated recleaned to take out all impurities smaller than the 10 grain, such as weed seed, wild oats, etcetera.

To this end, it consists primarily of a conveyor screw having a cylindrical screen secured on the periphery of the screw and set 15 at a substantial angle to the horizontal so that as the device is rotated at the proper speed, grain delivered into its lower end will be elevated by the screw action to the upper end where it is discharged, and during the 20 elevation the impurities are brought to the screen surface by gravity or the centrifugal action, and discharged through the screen, which is preferably enclosed by an imperforate cylinder spaced therefrom so that the 25 impurities can be collected and delivered wherever desired.

To illustrate my invention I annex hereto a sheet of drawings in which the same reference characters are used to designate identical parts in all the figures, of which:

Fig. 1 is a side elevation of a separator having my cleaning and elevating apparatus applied thereto, a portion of said apparatus being in section and otherwise broken away 35 to show the details thereof; and

Figs. 2 and 3 are sections on the lines 2—2 and 3—3, respectively, of Fig. 1.

The separator 10 may be of any ordinary construction, and, per se, forms no part of 40 my invention, which is adapted primarily as an attachment thereto. In the preferred form of separators, the thrashed grain is delivered into a transverse trough 11 located beneath the machine and having the customary screw conveyor 12 rotating therein. The trough 11 preferably terminates in a cylindrical portion 13 extending through the side of the separator and extending into the horizontal cylindrical portion 14 of a boot 45 casting 15 which is suitably secured to the framework of the separator. The main cylindrical portion 16 of the boot is preferably set at an angle of say forty-five degrees, and, of course, has its bottom closed and forming 50 the bearing for the lower end of the con-

veyor shaft 17, the upper end of which is journaled as will be subsequently described. The upper end of the cylinder 16 has the radially extending annular flange 18 connecting the cylindrical portion 16 with the 60 enlarged cylindrical portion 19 in which is secured the lower end of the elongated cylindrical casing 20. The upper end of this casing is closed by a head 21, which has the bearing therein for the upper end of the screw conveyor shaft 17, which has secured 65 on its upper end the miter gear 22 meshing with a corresponding gear 23 secured on the short shaft 24 journaled in a suitable bearing preferably formed on the head or cap 70 21, and having the belt pulley 25 secured on its outer end and driven by the belt 26 from the pulley 27 which is connected to any suitable shaft in the separator so as to rotate the conveyor shaft 17 at the proper rate 75 of speed, which rate will vary with the inclination of the shaft 17, as it will be obvious that for elevating purposes, the more nearly the apparatus is brought to a vertical position the faster the shaft 17 must revolve, 80 and the less must be the pitch of the screw 28 of the conveyor shaft 17. In some conditions, I prefer to have the casing 20 extend vertically, as indicated in dotted lines, 85 so that the appearance of the apparatus will 90 more nearly approach that of the elevators now in use.

The lower end of the conveyor screw cooperates closely with the interior of the cylindrical portion 16 of the boot so as to 95 elevate out of the boot the grain delivered thereinto by the screw 12. Above the cylindrical portion 16, the screw 28 is surrounded with the screen 29 which may be of wire mesh construction, and which is preferably supported by having the periphery of the screw 28 provided with the flange portion 30 extending therefrom substantially at right angles to the body of the screw and parallel to the axis of the shaft 17, and on 100 the outside of the cylindrical screen 29, I place a helical band 31 opposite the flange 30, and secure the two together with the screen clamped securely between them by the bolts or rivets 32 passed therethrough at 105 frequent intervals. To support the casing 20, I provide the cylindrical band or casing 33 surrounding the same and having the extension 34 bolted to the side of the separator, and to support the screen properly, 110

I locate thereon at suitable intervals the rings 35, which cooperate with the anti-friction rollers 36, see Fig. 3, journaled in suitable lugs 37 secured on the interior of the casing 20. At the upper end of the casing 20, I locate the plate 37^a extending across the same at right angles, and having an aperture therein of the proper size to receive the ring 38 secured on the upper end of the cylindrical screen. The plate 37 has a portion thereon extending out through an aperture 39 in the casing, and having the sides 40 to form a spout which opens into the swinging cylindrical spout 41, supported from the upper end of the casing 20 by the chains 42, so that the clean grain can be carried through the spout 41 to the wagon or other receptacle into which it is to be delivered. Where the apparatus is to be used in a vertical position, as shown in dotted lines, I will provide above the plate 37^a another plate 43 which is set at an angle and will serve to force the grain, as it were, to one side so that it will be discharged from the spout 40 into the weighing apparatus 44 indicated in dotted lines in Fig. 1.

The operation of my improved apparatus will be readily apparent. The rotation of the shaft 17 with the lifting action of the screw conveyor 28 carries the grain from the bottom of the boot up through the screen and delivers the same through the spout 40. As it travels upward, gravity and the centrifugal force will spread the grain over the surface of the screen and any impurities therein smaller than the grains will fall through the apertures of the screen and slide down the interior of the casing 20 until they reach the bottom where they pass out through the aperture 45 formed therein and into the spout 46 beneath which may be placed any desired receptacle.

While I have shown and described my invention as embodied in the form which I at present consider best adapted to carry out its purposes, it will be understood that it is capable of modifications and that I do not desire to be limited in the interpretation of the following claims except as may be necessitated by the state of the prior art.

What I claim as new and desire to secure by Letters Patent of the United States, is—

1. In a combined elevating and cleaning apparatus, the combination of a helical conveying screw set at a substantial angle to the horizontal, with a cylindrical screen secured on the periphery of the screw, and rotating therewith, means for rotating the screw and screen, means for delivering grain to the lower end of the screw, and a casing spaced away from the screen and surrounding it, and having an aperture therein at its lower end through which the screenings are discharged at a single point.

2. In a combined elevating and cleaning

apparatus, the combination with a horizontal conveyor screw and its casing, of a boot adapted to cooperate therewith and consisting of a main cylindrical portion terminating at its top in an enlarged off-set and a horizontal cylindrical portion into which the horizontal conveyor screw extends opening into the main portion, a cylindrical casing secured at its lower end in the offset, a cap for the top of the casing, a screw conveyor shaft journaled in the bottom of the boot and in the cap, means for rotating the shaft, a conveyor helix secured to the shaft and having its lower end cooperating with the boot, and a cylindrical screen surrounding and secured to the helix above the boot.

3. In an apparatus of the class described, a combination with a boot having an aperture therein through which the grain is received and having a main cylindrical portion in the bottom of which is a bearing, of a cylindrical casing secured at its lower end to the upper end of the cylindrical portion of the boot, a cap for the top of the casing, a screw conveyor shaft journaled in the bearing in the bottom of the boot and in the cap, means for rotating the shaft, a conveyor helix secured to the shaft and having its lower end cooperating with the boot, a cylindrical screen surrounding and secured to the helix above the boot, a plate extending transversely of the casing toward the upper end thereof and through which plate the upper end of the conveyor helix extends, and a spout connected with an opening in the side of the casing above the plate.

4. In an apparatus of the class described, a combination with a boot having an aperture therein through which the grain is received and having a main cylindrical portion in the bottom of which is a bearing, of a cylindrical casing secured at its lower end to the upper end of the cylindrical portion of the boot, a cap for the top of the casing, a screw conveyor shaft journaled in the bearing in the bottom of the boot and in the cap, means for rotating the shaft, a conveyor helix secured to the shaft and having its lower end cooperating with the boot, a cylindrical screen surrounding and secured to the helix above the boot, a plate extending transversely of the casing toward the upper end thereof and through which plate the upper end of the conveyor helix extends, a spout connected with an opening in the side of the casing above the plate, and a second plate above the first and inclined relative thereto so as to force grain delivered thereagainst toward the spout.

5. In a combined elevating and cleaning apparatus, the combination of a helical conveying screw set at a substantial angle to the horizontal, with a cylindrical screen secured on the periphery of the screw and rotating therewith but terminating short of

the lower end thereof, and a boot having a cylindrical portion with which the un-screened lower end of the screw co-operates, said boot having an opening thereinto for receiving the uncleaned grain.

6. In a combined elevating and cleaning apparatus, the combination of a helical conveying screw set at a substantial angle to the horizontal, with a cylindrical screen set 10 cured on the periphery of the screw and rotating therewith but terminating short of the lower end thereof, a boot having a

cylindrical portion with which the un-screened lower end of the screw co-operates, said boot having an opening thereinto for 15 receiving the uncleaned grain, and a casing forming a continuation of the boot and surrounding the screened portion of the screw and spaced away from the screen, and having an aperture therein through which the 20 screenings are discharged.

In witness whereof, I have hereunto set my hand this 27th day of June, 1925.

DANIEL W. DETWILER
